BABY SEAT

Giuseppe Gigante, % Dr. Ing. Misitano A.9,
Via Padova 217-20127, Milan, Italy

Filed Feb. 12, 1971, Ser. No. 115,145

Term of patent 3½ years

Int. Cl. D6—02

U.S. Cl. D15—1

FIG.1

FIG.2

FIG.3

FIG.4FIG.5FIG.6FIG.7FIG. 1 is a side elevational view, as seen from the right side of the FIG. 2, of the baby seat according to my new design;

FIG. 2 is a fore elevational view when viewed from the left side of FIG. 1;

FIG. 3 is a back elevational view when viewed from the right side of the FIG. 1;

FIG. 4 is a side elevational view as seen from the right side of the FIG. 2;

FIG. 5 is a sectional view corresponding to the middle plane of the FIG. 2;

FIG. 6 is a top view when viewed from the top of the FIG. 1;

FIG. 7 is a bottom view when viewed from the bottom of the FIG. 1.

I claim:
The ornamental design for baby seat, as shown and described.
